CLAIM

The ornamental design for a cordless impact wrench, as shown and described.

DESCRIPTION

FIG. 1 is a top, front and right side perspective view of a cordless impact wrench, showing my new design;
FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion labeled “9” in FIG. 3;

FIG. 10 is an enlarged view of the portion labeled “10” in FIG. 4; and,

FIG. 11 is an enlarged view of the portion labeled “11” in FIG. 8.

The broken lines show the features of the cordless impact wrench that form no part of the claimed design. The dot-dash broken line rectangle frames define the boundary of an enlarged view and form no part of the claimed design.
